UNITED STATES PATENT OFFICE.

JACOB RANZ, OF ST. LOUIS, MISSOURI.

SANITARY PILLOW.

1,274,595.

Specification of Letters Patent.

Patented Aug. 6, 1918.

Application filed January 17, 1917. Serial No. 142,797.

To all whom it may concern:

Be it known that I, JACOB RANZ, a citizen of the United States, and resident of St. Louis, Missouri, have invented certain new 5 and useful Improvements in Sanitary Pillows, of which the following is a specification.

This invention relates to improvements in sanitary pillows, and has for its object a 10 woven body constructed of a resilient material and so formed as to retain its proper shape but yet provide comfort to the head, and a suitable covering placed over the same for incasing the body, which covering is so 15 constructed as to be removed and replaced for cleansing purposes.

A further object of my invention is to construct a pillow which is absolutely sanitary, its body so shaped and designed as to 20 give comfort to the user, sufficiently resilient as to normally return to its original position when the weight of the head is removed; and in the body may be inserted suitable ingredients of a medicated nature when the 25 pillow is to be used for invalids or unhealthy persons.

Figure 1, is a perspective view of my invention with a part of the cover or casing broken away showing the resilient body.

30 Fig. 2 is a cross-sectional view of the same.

Fig. 3, is a central longitudinal sectional view.

In the construction of my invention I provide a pillow consisting of a body portion 35 constructed of a reticulated material such for example as a hardened screen 4, the ends of the frame are bent inwardly approximately at right-angles forming flanges 5, the corners 6 being sufficiently rounded so as to prevent injury to the person as well as to protect the covering or casing 7 which is placed thereover. This cover or casing is 40 constructed of a suitable fabric and in the shape of a sack, its one end 8 being closed while the opposite end 9 is suitably flapped and the edges 10 arranged to be tied or laced together in a manner found most desirable.

The woven resilient body is constructed of 45 an endless reticulated material, and the shape of the body in cross-section may be

preferably rounded, elliptical or oval as found most adaptable to the comfort of the person. In the illustration we show the shape approximately oval which is believed 55 will best conform to the head and shoulders of the person using the same.

The body is corrugated in a manner as that shown in Fig. 3. These corrugations being of such dimension as found most desirable 60 and the purpose of the corrugations is to give the resilient body a reasonable movement inwardly to conform with the head, without moving the ends. In addition to this the in-turned flanges 5 provide sufficient 65 stiffness and rigidity to support the ends from collapsing.

The pillow is especially designed to dispense with the usual filler such as feathers, moss, and the like, of which the ordinary 70 pillows are now constructed. It is light and soft and when the pillow is used by unhealthy persons the interior of the pillow may be packed or partially packed with herbs, or a light filler provided with medicinal properties so that the person may properly 75 inhale the odors expelled from the medicated properties as located within.

The pillow is also well adapted to warm or hot climates and the head kept cool by 80 means of proper ventilation passing through the pillow.

Having fully described my invention what I claim is:

A sanitary pillow constructed of a sheet 85 of woven spring wire, the body portion of the sheet being bent into corrugations, the ends of the sheet being connected together forming an oval-like hollow body, the outside edges of the body being turned inwardly 90 to provide additional rigidity to the body, and a casing of fabric placed over the woven body the ends being laced together, substantially as specified.

In testimony whereof, I have signed my 95 name to this specification, in presence of two subscribing witnesses.

JACOB RANZ.
